UNITED STATES PATENT OFFICE.

EARLE A. BERRY, OF KANSAS CITY, MISSOURI.

SILO.

1,104,866.

Specification of Letters Patent.

Patented July 28, 1914.

Application filed February 1, 1912. Serial No. 674,776.

To all whom it may concern:

Be it known that I, EARLE A. BERRY, a citizen of the United States, residing at Kansas City, in the county of Jackson and State of Missouri, have invented certain new and useful Improvements in Silos; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to silos and has for its principal objects to provide a silo of stave construction having means whereby successive staves may be connected and supported while being assembled, to facilitate the building of the structure and to hold the parts together when their intimate relations have been altered through exposure or from other cause; to provide improved bracing means for obviating mis-shapement of the structure under the influence of strong winds; to provide an improved door frame having means for bracing the jambs apart, and to provide a removable feed chute which may be applied to the silo or removed therefrom by the user, either while the structure is being erected or afterward. In accomplishing these objects, I have provided the improved details of a structure hereinafter described and illustrated in the accompanying drawings, wherein:

Figure I is an elevation of a silo constructed according to my invention. Fig. II is a cross-section of same on the line II-II Fig. I, showing the brace rods. Fig. III is an enlarged cross-sectional view of a portion of the silo, showing the dowel hoop. Fig. IV is an enlarged perspective view of a portion of the silo, a part of the body being broken away to show the dowel hoop. Fig. V is an enlarged detail view of a part of one of the door frame braces, a portion being broken away to show the connection of the individual parts. Fig. VI is an enlarged detail view of a part of the frame and ladder, showing the connection of the ladder with the frame. Fig. VII is an enlarged perspective view of one of the chute sections, showing its mounting.

Referring more in detail to the parts, 1

designates the body of the silo, which is made up of a number of individual staves, 1' having tongue and groove connection to form a tight inclosing structure. In the side of the silo is an opening 2 which runs from top to bottom and contains a door-frame comprising a pair of upright stave members 3, having sockets 3' therein spaced at intervals throughout its length by brace sections 4, each of which is made up of individual short staves 5, having tongue and groove connection, as in the main structure, and united by dowel pins 6 which extend through transverse bores 7 in the staves. The brace members formed as described are mounted between the door-jambs and held permanently in position by the ends of dowel pins 7, which project into sockets 9 in the edges of the door jambs. The spaces between the braces 4 may be closed by doors 10, of any suitable structure, having fastenings by which they may be applied to or removed from the door-frame at will, but preferably provided with elongated handle portions 11, which may serve as rungs of a ladder for use in climbing to the top of the silo.

Each of the staves of the body 1 has a transverse bore 12 near its upper end for containing a dowel hoop 13, the hoop preferably comprising a steel rod of slightly less diameter than the bores 12 so that the bore may be straight through each stave and the rod extend in a curved path therethrough. I preferably make the dowel hoop in two sections each of which is adapted to extend half way around the silo and project at opposite ends from the jamb and middle staves, so that it can connect with the adjoining jambs and body staves, thereby facilitating the assembling of the silo, as will presently be described.

I prefer to provide but one of the dowel hoops, but place ordinary hoops 15 around the silo at intervals throughout its height in order to hold the parts together, such hoops being provided with turnbuckles 16, by which they may be tightened when the structure is erected, and afterward, to take up shrinkage.

In order to afford access to the door openings of the silo I place a ladder 17 in front of the door frame, the rungs 18 of which are arranged above and below the door open-

ings, as shown. I prefer to attach the rungs of the ladder to the side runners by bolts 19, having nuts 20 on their outer exposed ends, and having hooks 21 on their inner ends adapted to bear against the door jambs. The ladder is placed against the door frame before the hoops 15 are tightened so that the latter may drop into the hooked ends of the ladder bolts and anchor the ladder firmly against the frame. It is apparent that when the hoops are tightened by manipulation of the turnbuckles the ladder is held against the body of the silo and cannot be released except by loosening the body hoops. 15 When the silo is filled with ensilage of a dry nature the latter must be removed through the door openings for feeding. It is apparent that with a high wind this ensilage would be blown away and lost if 20 thrown through a door opening. I therefore provide a chute through which the ensilage may pass directly down the side of the silo into a wagon, or onto the ground, to obviate loss by being scattered by the 25 wind. This chute comprises semi-circular sections 22 of stiff sheet metal, the edges of the sections being turned inwardly to form attaching lips 23, having bolt holes 24 adapted to register with the ladder bolt holes so 30 that the lips may be projected between the ladder runners and the door-frame, and the hook-bolts for connecting the ladder with the frame be projected through the lip apertures so that when the nuts are tightened. 35 on the ladder bolts the chute lips may be clamped between the runners and the frame or between the runners and the ladder rungs. It is apparent that with this construction the chute may be erected in sections, each 40 section being of such diameter that the builder may work within the chute to fasten same to the silo.

It is a well known fact that with the silos of stave construction high winds blowing 45 against one side of the silo will tend to flatten same to an oval shape, thereby separating the staves and forming cracks through which the ensilage is exposed to the weather. While the ordinary braces tend 50 to some extent to prevent such mis-shapement, they are not altogether successful, and for that reason I have provided the improved brace shown herein, comprising the rods 25 which extend diametrical across the 55 interior of the silo body and have hooks 26 at their ends which connect with the eyes 27 of bolts 28 which extend through staves on opposite sides of the silo. On each of the bolts 28 is a hook 29 having an enlarged 60 washer-like body 30 carried by the bolt and bearing against the side of the silo. Connected with each of the hooks 29 is a guy rod or wire 31 which may be connected with an anchor 32 set a proper distance from 65 the base of the silo. Each of the brace rods

25 has a turn buckle 33 by which the rod may be tightened or extended as required.

In assembling the silo, scaffoldings are erected a short distance apart and the door frame properly set and braced to the scaffolding, the end of one of the dowel hoop sections is then projected into a socket on one of the jambs and the staves strung thereon, the second hoop section being connected with the last stave strung on the first hoop 75 and the last half of the silo body being strung on that section until when the last stave is in place the projecting end of the hoop is stuck into a socket 3' in the door-jamb. The outside hoops are then arranged 80 in place, the ladder being first raised against the door-frame so that the hoops may drop into the hook-bolts, as hereinafter described. The outside hoops may then be tightened to bring the staves into close relation and the 85 cross-braces installed and guyed to the ground. If a chute is to be erected with the silo the sections may be applied to the ladder while the ladder is on the ground, or, if desired, the sections may be applied to the 90 ladder after the ladder is connected with the silo. With this latter plan, the sections must be arranged singly and the nuts removed from the rung bolts so that the lips of the 95 chute may be applied thereto, the nuts being 100 afterward applied to the bolts so that they will bear against the chute lips. The sections of the chute are overlapped on the outer upper edges to prevent rain or snow from entering through the horizontal cracks.

It is apparent that expansion and contraction of the material cannot destroy a structure of this kind as the interior dowel hoop will hold the staves in proper relation even should wide cracks form therebetween, 105 and by providing sufficient space in the dowel sockets in the door-jambs the diameter of the silo may be reduced by tightening the outer hoops and thereby take up the contraction and bring the staves into 110 their original close relation. It is also apparent that by providing the opposite guy members, wind pressure is taken up wholly or mainly by said guy members, so that there is little probability of misshapement of the 115 silo.

Having thus described my invention, what I claim as new therein and desire to secure by Letters-Patent is:—

1. A silo comprising a body member having hoops extending therearound, and a ladder comprising runners and rungs, and bolts connecting the rungs with the runners and having hooks at their inner ends adapted for receiving the body hoops, substantially as 120 set forth.

2. A silo comprising a body member, a ladder connected with said body member and having runners, and rungs connected with said runners by suitable bolts, and a chute 130

member having edge lips provided with apertures adapted to seat over said bolts for the purpose set forth.

tures adapted to seat over said bolts and between the ladder runners and rungs. 10
In testimony whereof I affix my signature in presence of two witnesses.

EARLE A. BERRY.

3. A silo comprising a body member, a ladder connected with said body member and having runners and rungs connected with said runners by suitable bolts, and a chute member having edge lips provided with aper-

Witnesses:
